Primary Examiner — John R Yeh

(74) *Attorney, Agent, or Firm* — Rumit Ranjit Kanakia

(57) **CLAIM**

The ornamental design for a bluetooth speaker, as shown and described.

DESCRIPTION

FIG. 1 is a first perspective view of a bluetooth speaker showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the bluetooth speaker thereof; and,

FIG. 10 is an enlarged view of the selected portion 10 in FIG. 1.

The dash-dash broken lines depict portions of the bluetooth speaker that form no part of the claimed design. The dot-dash lines depict the enlargement indications and form no part of the claimed design.

1 Claim, 10 Drawing Sheets
